UNITED STATES PATENT OFFICE.

CLAUDE WILLIAM DENNY, OF LONDON, ENGLAND.

REINFORCED METAL.

1,323,167.

Specification of Letters Patent. Patented Nov. 25, 1919.

Application filed November 6, 1918. Serial No. 261,382.

To all whom it may concern:

Be it known that I, CLAUDE WILLIAM DENNY, a subject of the King of Great Britain, residing at London, England, have invented certain new and useful Improvements 5 in Reinforced Metals, of which the following is a specification.

This invention relates to the production of composite or built-up metal plates, sheets, 10 tubes or other articles, same being composed of two or more layers of different metals, such as relatively soft and expensive metals like copper, lead, brass, aluminum and the like, reinforced with a base metal such as 15 iron or steel to give strength and stability and also to economize in the use of the softer metal.

The object of the present invention is an improved method of applying and securely 20 uniting the layers of the different metals.

According to the said invention the reinforced or composite metal is produced by perforating a metal plate or tube and applying the softer covering metal to one or both 25 sides thereof (the perforated plate being either in the flat or formed into a tube) by electro-deposition, so that the said covering metal enters the perforations of the plate or tube and is keyed or locked to the latter.

Figure 1 of the accompanying drawings 30 is a section, and

Fig. 2 is an elevation, of a perforated foundation plate which is used in the production of a composite plate in accordance 35 with this invention, by a process of electro-deposition.

Fig. 3 is a section of the plate at one stage 40 of the electro-deposition, the covering metal being in the process of being built-up upon the foundation or core.

Fig. 4 is a section of the finished composite or reinforced plate.

Fig. 5 shows a modification where the softer covering metal is applied to one side 45 only of the foundation plate.

Fig. 6 represents the use of two foundation plates laid together, and

Fig. 7 shows how the covering metal is applied and keyed to the said two foundation plates.

Fig. 8 illustrates the use of a foundation or core plate built up of several layers.

Fig. 9 is a cross-section, and Fig. 10 an elevation, showing a tube adapted to form 55 the foundation of a composite or built-up tube in accordance with this invention.

Fig. 11 is a section of the finished tube.

Fig. 12 represents a section showing how the softer or covering metal may be applied to the outside only of the tube.

Fig. 13 shows how the said covering metal may be applied to the inside only of the tube.

Referring to Figs. 1 to 4, to produce a sheet or plate of reinforced copper or the like, a sheet of iron or steel *a* is taken (Fig. 1) which is perforated by punching circular holes *b* in it, or holes or slots of any suitable shape. Said holes *b* are preferably of a slightly taper formation, as shown.

The surface of the sheet *a* is now cleaned and prepared for electro-deposition by any of the well-known methods, and copper is deposited upon the surface of both sides of the sheet and upon the walls or sides of the holes *b*, as shown in Fig. 3. The copper *c* gradually builds up upon the iron or steel surface until the holes *b* are completely filled, as shown in Fig. 4, the two copper facings being securely keyed or locked to the iron or steel by the connecting parts *c*¹ filling the said holes *b*. The composite sheet can now be worked up, after annealing, into manufactured articles.

Instead of the copper *c* being applied upon both sides of the iron or steel plate *a*, it may be deposited upon one side only, as shown in Fig. 5, the taper holes *b* being arranged as shown, and being filled up by the copper, forming keys *c*¹ integral with the copper facing *c*.

Or, as represented in Figs. 6 and 7, two iron or steel plates *a*, *a*, may be placed back to back, with the larger diameters of the tapering holes *b* coinciding. The plates are then temporarily fixed together and copper is deposited upon them until the holes *b* are entirely filled, as seen in Fig. 7, the two facings of copper being joined together by the keys or connecting parts *c*¹ filling the said holes.

Instead of thick iron or steel foundation plates being used the foundation may comprise two or more thin plates or layers, as shown in Fig. 8, where three such layers *a* are indicated. These thin plates are collectively punched with holes *b* and the copper facing *c* is electro-deposited in the manner previously described. With this construction a certain amount of flexibility is imparted to the composite plate.

In the application of the invention to

tubes, as shown in Figs. 9 to 11, the main body of the tube may be made from a flat strip or metal *a*, pierced with taper holes *b*, and bent up into tubular form, as in Fig. 9, the meeting edges being welded together. Copper is then deposited by electrolysis upon the inside and outside faces, as at *c*, Fig. 11, the interior and exterior facings being joined together and locked to the tube *a*, by the integral connecting pieces *c*¹ filling the holes *b*. The tube may be finished, if necessary, by drawing it through dies.

As shown in Fig. 13, the copper facing *c* may be applied only to the outside face of the tube *a*, being locked to the latter by the keying parts *c*¹ filling the taper holes *b*.

Or, as seen in Fig. 13, the copper *c* may be deposited only upon the inner face of the tube *a* and held to the latter by the keys *c*¹ engaging the holes *b*.

In all cases the finished plates or articles may be improved by passing the same through finishing rollers or by burnishing them mechanically.

Having fully described my invention, what I desire to claim and secure by Letters Patent is:—

1. The production of reinforced or composite metal sheets, plates, tubes and the like consisting in perforating a rigid metal foundation and applying a softer covering metal to the surface of said foundation by electro-deposition in one continuous process, and so that the said covering metal enters and fills

the perforations flush with the main surface 35 of the covering metal upon the non-perforated part of the foundation, and is mechanically locked to the said foundation.

2. The production of reinforced metal sheets, plates, tubes and the like consisting 40 in forming tapered perforations in a rigid metal foundation and applying a softer covering metal to the surface of said foundation by a single continuous process of electro-deposition, so that the said covering 45 metal enters and fills the tapered perforations flush with the main surface of the covering metal upon the non-perforated part of the foundation, and is mechanically locked to the said foundation. 50

3. The manufacture of reinforced tubes consisting in perforating a rigid foundation plate of metal, bending it into a tubular form and joining the edges, and applying a covering metal by electro-deposition in a 55 single continuous process, to the surface thereof, so that it enters and fills the perforations, producing a flush surface and is mechanically locked to the perforated foundation. 60

In testimony whereof I have hereunto set my hand in presence of two subscribing witnesses.

CLAUDE WILLIAM DENNY.
